CAPSULE FOR DENTAL MATERIALS OR SIMILAR ARTICLE

Stephen L. Hiltebrant, Rocky River, and Reinhold Wilhelm Petruschke and Reinhold William Petruschke, Kirtland, Ohio, assignors to The Columbus Dental Manufacturing Company, Columbus, Ohio

Filed Aug. 22, 1972, Ser. No. 282,673

Term of patent 14 years

Int. Cl. D24—02

U.S. Cl. D24—1 A

FIG. 1 FIG. 2

FIG. 3

FIG. 4

FIG. 1 is a perspective view of a capsule for dental materials or similar article, showing our new design;

FIG. 2 is a side elevational view;

FIG. 3 is a top plan view; and

FIG. 4 is a view similar to FIG. 1, but showing the lid in an open position.

We claim:

The ornamental design for a capsule for dental materials or similar article, substantially as shown and described.
